UNITED STATES PATENT OFFICE.

HERMAN J. ADLER, OF CLEVELAND, OHIO, ASSIGNOR TO J. E. STEVERDING, OF CLEVELAND, OHIO.

DETERGENT COMPOUND FOR CLEANING WINDOW-SHADES, &c.

1,278,411.

Specification of Letters Patent. Patented Sept. 10, 1918.

No Drawing.

Application filed May 13, 1918. Serial No. 234,254.

To all whom it may concern:

Be it known that I, HERMAN J. ADLER, a citizen of the United States, residing at Cleveland, in the county of Cuyahoga and

5 State of Ohio, have invented certain new and useful Improvements in Detergent Compounds for Cleaning Window-Shades, &c., of which the following is a specification.

This invention relates to detergent compounds, and especially those particularly adapted for cleaning window shades and similar fabric, and has for its object to provide an improved compound of this kind which will remove dirt from shades or the 10 like without leaving marks on the articles.

An advantage of the compound is that it has the form of a powder, and can be applied dry, and by the use of a brush or cloth it may be rubbed over the surface of the 15 shade or fabric and will pick up and take off the dirt thereon.

The compound comprises a mixture of the following ingredients: powdered pumice; soda ash; silex (or oxid of silica) and 20 fullers' earth. These ingredients are preferably combined in the following proportions: one-third part of pumice; one-third soda ash; one-sixth silex; and one-sixth fullers' earth.

25 When these ingredients are mixed to-

gether they form a powder, and in the use of the same it is applied to the surface of the shade or other article in a dry state, by sprinkling or dusting the same thereon. Then it is rubbed with a brush or cloth and 35 the dirt will be taken up and can be brushed off.

The pumice has by reason of its gritty qualities the function of abrading the dirt deposits, and the silex has somewhat similar 40 qualities; while the soda ash and fullers' earth are believed to assist in the eradication of grease spots and the like by absorbing the same.

I claim:

45 1: A cleaning compound comprising powdered pumice; soda ash; silex and fullers' earth.

2. A cleaning compound comprising the following ingredients in substantially the 50 proportions stated: powdered pumice, one-third; soda ash, one third; silex, one-sixth; and fullers' earth, one-sixth.

In testimony whereof, I do affix my signature in presence of two witnesses.

HERMAN J. ADLER.

Witnesses:

ROBERT N. MACKIE,
JOHN A. BOMMARDT.
